UNITED STATES PATENT OFFICE.

BURTON S. DE BALL, OF CHICAGO, ILLINOIS.

BOILER-FURNACE.

No. 896,440.

Specification of Letters Patent. Patented Aug. 18, 1908.

Application filed July 18, 1907. Serial No. 384,423.

To all whom it may concern:

Be it known that I, BURTON S. DE BALL, a citizen of the United States, residing at Chicago, county of Cook, and State of Illinois, have invented certain new and useful Improvements in Boiler-Furnaces, of which the following is a specification.

My invention relates to stationary steam boiler furnaces and the object of my invention is to provide a furnace as mentioned, which will more perfectly consume the fuel, to the end that a greater efficiency shall be obtained from the quantity of fuel burned, thereby requiring less fuel for a given amount of work; and that the discharge of smoke from the furnace shall be reduced to a minimum or entirely prevented.

Other objects will appear hereinafter.

With these objects in view my invention consists in a furnace of the novel construction and arrangements of parts all as will be hereinafter fully described and particularly pointed out in the claims.

My invention will be more readily understood by reference to the accompanying drawings forming a part of this specification and in which,

Figure 1 is a vertical longitudinal section of a boiler furnace embodying my invention in its preferred form, Fig. 2 is a horizontal longitudinal section on the line, $x-x$ of Fig. 1, Fig. 3 is a transverse section of the line $y-y$ of Fig. 2, Fig. 4 is a similar section of the line $z-z$ of the same figure and Fig. 5 is a detail sectional view on substantially the line, $w-w$ of Fig. 2.

Referring to the drawings, 1 indicates a boiler of any ordinary or preferred form. This is set in the usual masonry comprising the side walls, 2 the back wall, 3 and the front, 4.

5 indicates the furnace grate and 6 the bridge capped with fire-brick, 7.

Generally speaking my invention consists in injecting or spraying superheated air into the furnace above the grate, in such a manner as to intimately mix a large quantity of air with the normal products of combustion, consisting of gases and smoke. By superheating the air previously to injecting it into the furnace, the combustion is not retarded, as would be the case with cold air, no matter how great the quantity of air admitted; but to the contrary, the combustion is greatly facilitated. To accomplish this end, I provide air supply pipes extending substantially

to the length of the furnace and located preferably in the hottest portion thereof, and connect them with air spraying devices located in the front wall of the furnace and 60 preferably between the fuel doors. As an auxiliary or supplementary air injector, I provide an air supply pipe extending transversely of the furnace through the bridge and equip the same with means for injecting 65 small jets or streams of air into the hot gases and smoke as they pass over the bridge.

Again referring to the drawings, 8 indicates the air supply pipes communicating with the front air injector or sprayers. I 70 have shown two such pipes, one on each side of the furnace, but wish it understood that but one pipe of sufficient size for an ample supply of air may be used without departing from the scope of my invention. The pipes, 75 8 are embedded in the side walls, 2, for protection, and so as not to reduce the combustion space; and are located close up to the boiler to receive the greatest amount of heat in order that the air passing there through 80 shall be thoroughly superheated before reaching the sprayers. The rear ends are bent outwardly through the walls as at 9, to communicate with the atmosphere, and at their forward ends are bent downwardly as at 10, to 85 communicate with a transverse pipe, 11. The pipe, 11 is arranged slightly above the tops of the fuel doors, 12 and is provided with down pipes, 13 extending into the air sprayers, 14. 90

The sprayers, 14 each comprise an iron box provided with an inward extension, 15 which projects beyond the inner face of the wall, 4 and which is provided with a large number of small holes, 16 forming nozzles through 95 which the air is sprayed in all directions into the burning gases. The bottom of the projection, 15 is arched as shown to facilitate removing or inserting the grate bars, 5, also to provide a suitable wall for the holes or jets 100 16^a to direct the hot air downwardly into the gases. To facilitate the influx of air, a steam injector, 17 may be provided, or the rear end of the pipe, 8 may be connected to a blower, 18.

The front wall is of novel construction and 105 will now be described. 20 indicates the usual "dead plate", arranged above the ash pit doors, 21 and forming the bottom facing of the fuel doors, 12. Upon the dead plate are placed the sprayers, 14. These fill the 110 spaces between the doors, 12 and their side walls form the side facings of the fuel open-

ings. The "liner" 22 rests upon the spray-
ers, 14, and is provided with lugs, 23 which
retain the members, 14 in place. Above the
liners, 22 and below the dead plate, 20 the
wall is of the usual masonry construction.

By injecting a large quantity of hot air
into the furnace and intimately mixing it
with the partially burned products of com-
bustion, practically all of the smoke is con-
sumed. However, some little especially
from the rear end of the grate will pass over
the bridge, 6. In order to completely burn
this small residue of smoke, I provide an aux-
iliary air injector which will intimately mix a
quantity of hot air with the gases and remain-
ing smoke as they pass over the bridge. Ex-
tending transversely of the furnace, through
the bridge, 6 is a pipe 25. This may be in
communication with the atmosphere at
either or both ends and is provided with a
large number of jets, 26. The pipe 25 is em-
bedded in the masonry below the firebrick, 7
and the jets, 26 extend between the bricks to
substantially a level with the top of said
bricks. The air mixed with the gases at this
point completes the combustion of the smoke.
There is no need of forcing the air through
the pipe, 25, as the rapidly moving gases will

create sufficient suction to draw in a large
quantity of air.

Having described my invention what I
claim as new and desire to secure by Letters
Patent is:

In a device of the class described, a boiler
and its furnace, said furnace including the 35
side walls and a front wall having the usual
fuel openings, in combination with a plural-
ity of air spraying devices forming the por-
tion of said front wall between and upon each
side of said openings and forming the side 40
facings thereof, each said device comprising
a rectangular box-like member provided with
an inwardly extending portion having an
arched underface overhanging the grate, a
pipe embedded in said front wall above said 45
devices, a short down pipe, extending from
said pipe into each of said spraying devices
and means for supplying air thereto, substan-
tially as described.

In testimony whereof I have signed my 50
name to this specification in the presence
of two subscribing witnesses.

BURTON S. DE BALL.
